BOLT MECHANISM FOR RIFLES

John D. Pedersen, Jackson, Wyo.

Original application July 29, 1939, Serial No. 287,221. Divided and this application March 13, 1943, Serial No. 478,996.

2 Claims. (Cl. 42—16)

The present invention relates to an improvement in bolt mechanism for rifles, and more particularly rifles of the semi-automatic type such as shown in my copending application Serial No. 287,221, filed July 29, 1939, Patent No. 2,330,737, dated September 28, 1943, of which this application is a division.

The bolt mechanism of the present improvement is of the combined rotary and reciprocatory type, being rotated between locked and unlocked positions and being reciprocated for opening and closing the breech and magazine chamber. It is presented herein in two alternate forms, one of which is an assembly of cover, carrier and bolt and the other merely an assembly of cover and bolt, this second form showing a cover which combines its own functions with that of a carrier. Both of these forms present a substantially smooth uninterrupted closure for the breech to prevent the intrusion of dirt.

Referring to the drawings which show said bolt mechanism and its preferred embodiments,

Fig. 1 is a longitudinal section through the receiver and part of the stock and barrel of a rifle showing the bolt mechanism in breech closing position;

Fig. 2 is a similar longitudinal section showing the bolt mechanism in the open and fully retracted position;

Fig. 3 is a top view of the bolt assembly;

Fig. 4 is a section through the bolt assembly generally on line 4—4 of Fig. 7;

Fig. 5 is a rear end view of the bolt assembly, the bolt being in its unlocked position;

Fig. 6 is a section on line 6—6 of Fig. 4;

Fig. 7 is a front end view of the bolt assembly, the bolt being in its unlocked position;

Fig. 8 is a fragmentary view of the carrier front end, showing in dotted lines the position of the ejector plunger when the bolt is in the unlocked position;

Fig. 9 is a similar fragmentary front view of the carrier. In this view the ejector plunger (dotted) is in the position for detaching the bolt from the carrier;

Fig. 10 is a fragmentary section on line 10—10 of Fig. 7 to give a side view of the bolt stop shoulders;

Fig. 11 is a projected view of the stopping shoulders of Fig. 10 looking in the direction of the dotted projection lines connecting said figures;

Fig. 12 is a rear end view of the bolt shown in Fig. 10;

Fig. 13 is a fragmentary section through the

receiver near its front end, to show the front end view of the bolt in its locked position;

Fig. 14 is a fragmentary section through the receiver near its front end, to show the front end view of the bolt in its unlocked position;

Fig. 15 is a section on line 15—15 of Fig. 1. In this position the bolt is locked;

Fig. 16 is a section on line 16—16 of Fig. 1. In this position the bolt is locked;

Fig. 17 is a section on line 17—17 of Fig. 2. In this position the bolt is unlocked;

Fig. 18 is a section on line 18—18 of Fig. 2. In this position the bolt is unlocked;

Fig. 19 is a fragmentary unrolled section on line 19—19 of Fig. 16, showing the firing pin in its forward position;

Fig. 20 is a fragmentary unrolled section on line 20—20 of Fig. 18, showing the firing pin in its retracted position;

Fig. 21 is a fragmentary unrolled section on line 21—21 of Fig. 13, showing the fully locked position of the bolt;

Fig. 22 is a fragmentary unrolled section similar to Fig. 21, but showing the bolt in nearly its unlocked position;

Fig. 23 is a fragmentary unrolled section on line 23—23 of Fig. 14, showing the fully unlocked position of the bolt;

Fig. 24 is a fragmentary unrolled section on line 24—24 of Fig. 13, showing the left lug of the bolt in the locked position;

Fig. 25 is a fragmentary unrolled section similar to Fig. 24, but showing the bolt in nearly its unlocked position;

Fig. 26 is a fragmentary unrolled section on line 26—26 of Fig. 14, showing the bolt fully unlocked;

Fig. 27 is a top view of the assembled bolt and carrier of alternate construction. The bolt is in the unlocked position;

Fig. 28 is a section on line 28—28 of Fig. 31;

Fig. 29 is a rear view of the assembled bolt, in the unlocked position;

Fig. 30 is a section on line 30—30 of Fig. 28;

Fig. 31 is a front view of the assembled bolt;

Fig. 32 is a fragmentary unrolled section on line 32—32 of Fig. 29, but with bolt locked and firing pin forward;

Fig. 33 is a fragmentary unrolled section on line 32—32 of Fig. 29, showing the bolt unlocked and the firing pin retracted;

Fig. 34 is a section on line 30—30 of Fig. 28, but with the bolt turned to its position ready to detach from the cover;

Fig. 35 is a section on line 35—35 of Fig. 28;

Fig. 36 is a group view showing respectively from left to right, the rear, right side, and front of the ejector; and

Fig. 37 is a fragmentary section through the carrier on section line 37—37 of Fig. 35 and showing top of bolt.

Referring to Figs. 1 and 2 which show sectional views of the breech action in which the present improved bolt is embodied, 1 indicates the receiver, 2 the barrel, 46 the stock, and 101 the guard member. Other details of this mechanism form no part of the subject matter claimed in this application and are more fully described in my companion application of which this is a division.

In Fig. 1 the breech action is in closed position, in Fig. 2 in open position. The breech action comprises a reciprocable and rotatable bolt 139 which is provided with a pair of oppositely located breech locking lugs 140, 141, Fig. 3, adapted to lock ahead of the receiver locking shoulders 142, 143. Fig. 13 is a front view of the bolt in its locked position, while Fig. 14 shows the bolt rotated to its unlocked position and ready to be moved longitudinally in the receiver 1.

The left bolt lug 140 is shown in the locked position engaged with receiver locking shoulder 142 in Fig. 24. Fig. 25 shows the left bolt lug nearly unlocked from the receiver shoulder 142. During this portion of the unlocking movement the bolt has been cammed toward the rear by the low pitch helix 142a of the receiver acting on the front end helix 144 of the left bolt lug 140. Fig. 26 shows the completely unlocked position of the bolt lug 140 which has been still further cammed toward the rear by the steep pitch helix 145 of the receiver acting on the helix 146 of the bolt lug. The two stages of camming to the rear constitute the primary extraction which, acting through the extractor 147, starts the fired case from the chamber 148 of the barrel. This primary extraction movement also serves as an easy transition from the rotary to the rectilinear motion of the bolt.

Radially extending from the front of right bolt lug 141 is the arm 149 which occupies the helical cam slot 150 in the enlarged rear end 85a of the slide bar 85 which is adapted to move longitudinally on the receiver, Figs. 13 and 14. Fig. 21 shows the arm 149 held downwardly by the rear helix 151 of the cam slot 150. This is the locked position of the bolt and corresponds to the position of the bolt lug 140 shown in Fig. 24, and the bolt shown in Fig. 13. Fig. 23 shows the arm rotated to its fully unlocked position by the helix 152 of the cam slot 150. This is the fully unlocked position of the bolt and corresponds to the position of the bolt lug 140 shown in Fig. 26, and the bolt shown in Fig. 14. Fig. 22 is the intermediate position in the unlocking of the bolt arm and corresponds to the bolt position shown in Fig. 25.

In the closing cycle of the breech action, when the cam slot 150 pulls the bolt forward, the squared ledge 153 of the cam slot, Fig. 23, moves forward to contact the squared back face 154 of the bolt arm 149 and to thereby pull the bolt forward without imparting a rotative tendency to the bolt. During this forward travel, the bolt is held from rotation by the left bolt lug 140 occupying the slot 155 in the receiver as shown in Figs. 26 and 14.

When the bolt reaches nearly to its forward position, its left lug helix 146 comes in contact with the helix 145 of the receiver, see Fig. 26. This contact deflects the left lug upward to the

position shown in Fig. 25. This portion of the rotation of the bolt moves the bolt arm 149 downward off contact with the ledge 153 of the cam slot 150 to the position shown in Fig. 22. The continued forward travel of the slide causes the helix 151 of the cam slot 150 to ride down the bolt arm 149 to the locked position of the bolt as shown in Fig. 21, in respect of the bolt arm 149 and by Fig. 24 in respect of the left bolt lug 140.

10 It should be understood that the right bolt lug 141, Figs. 3, 13, 14, is freed from or is in engagement with the right receiver locking shoulder 143 shown in Fig. 14, simultaneously with the freeing or engagement of the left bolt lug 140 from or 15 with the left receiver locking shoulder 142.

The bolt 139 is rotatably mounted in a bolt carrier 204, which is slidable in the receiver 1. The extractor 147 is mounted in the bolt in a radially directed T-slot 192, Fig. 3. The T-slot slopes 20 slightly to the rear and the movement of the extractor is rigidly controlled so that, as it moves outward from the cartridge rim the extractor claw 194 moves also slightly to the rear. This rearward inclination of the extractor path prevents the claw 194 from slipping off the cartridge rim during extraction. The extractor plunger 195 urged forward by the extractor spring 196 tends at all times, through the camming contact of face 197 of the plunger and surface 198 of the extractor, to force the extractor into engagement with the cartridge rim.

The ejector 199 is at all times urged forward by the ejector spring 200. The rear end of the spring 200 is supported by the plunger 201. The front end of the plunger furnishes a stop to limit the rearward movement of the ejector 199. A retaining pin 203 necked at its mid-portion serves to retain the plunger 201 in the bolt when the bolt is separated from the carrier 204, see Figs. 1, 2, and 4.

The bolt's rear end 205 is cylindrical for being journaled in the carrier 204. The bolt is retained therein by the tooth 206 of the bolt (Fig. 10) engaging behind a lug 207 of the carrier (Fig. 4). The forward part of the lug 207 has cut therein a segmental recess 208 in which the rear end of the plunger 201 rides when the bolt is rotated from its locked to its unlocked position.

Fig. 8 shows the plunger 201 (in dotted lines) 50 against a stop end 209 of the recess 208 thus preventing the bolt from rotating beyond its unlocked position when the bolt and bolt carrier are removed from the receiver. An inclined cut 210 through the bottom of lug 207, Figs. 4, 8, and 9, 55 allows the introduction of a pointed instrument to depress the plunger 201 against the tension of its spring 200, and thus permits the bolt to be rotated beyond its unlocked position to its disassembled position, Fig. 9, where the tooth 206 on 60 the bolt clears the lug 207 of the carrier. The bolt may now be drawn forward out of the carrier.

The carrier 204, in which the bolt 139 is mounted, has only reciprocatory motion in the receiver. A left rib 211 of the carrier is constantly guided in the slot 155 of the receiver, Figs. 1, 2, 13, 14, 17, etc. The slot 155 also is the guide for the left bolt lug 140 when the bolt reciprocates in the receiver.

The cover 202, Figs. 3, 4, 15, etc., is slidably connected to the carrier 204 by the ribs 212, 213 of the carrier, engaging in grooves 214, 215 of the cover. The rear end of the right rail 216 (Fig. 3) of the cover is guided by the groove 75 155a, Fig. 17, of the receiver when the bolt is in

its forward position and the rail 216 reciprocates back in receiver groove 155a when the bolt is being opened. The cover 202 therefore, aids in the guiding of the carrier 204 in the receiver.

The cover is assembled onto the carrier prior to the bolt being assembled to the carrier. The cover has endwise movement on the carrier, between the shoulder 217 of the carrier and shoulder 218 of the bolt, Figs. 1, 2, and 4. This endwise movement is limited by the rear lug 219 and forward lug 226 of the cover, Fig. 4. When the bolt is back in its open position, the cover is moved to its forward limit on the carrier, Figs. 2, 3, and 4. As the bolt moves forward to its closed position, Fig. 1, the front left end 221 of the cover stops against the shoulder 222 of the receiver, Fig. 2, the bolt and carrier continuing to move forward to the closed position. The cover is held forward to the stop 222 of the receiver by the shoulder 217 of the carrier, Fig. 1. The rear end of the cover thus extends to the rearward of the carrier and covers the space between the rear end of the carrier and the end 223 of the receiver opening, Fig. 1, when the bolt is closed.

The firing pin 224 is journaled at its rear portion in the carrier 204 and its forward reduced end 226 projects through the bolt face, and fires the cartridge in the chamber when its rear end 225 is struck by the hammer 127, Fig. 1. The rear end 205 of the bolt is slotted crosswise at 227, Figs. 12, 15, and 17. Into this slot engages a flattened intermediate wing 228 of the firing pin. The firing pin, therefore, while it has end movement independent of the bolt, must rotate with the bolt. The rear end 225 of the firing pin has a lateral lug 229 whose forward face is provided with a helical cam 230, Fig. 4. Fig. 19 shows the position of lug 229 when the firing pin is forward in the firing position. Fig. 20 shows the position of lug 229 of the firing pin when the bolt is unlocked, the firing pin having been fully retracted by the helical cam 231 of the carrier as it rotated with the bolt to the unlocked position of the latter. The firing pin is assembled to the carrier from the rear, the flattened wind portion 228 entering through grooves 232, 233 in the bore of the carrier, Fig. 6.

The bolt is next inserted into the carrier so that the wing portion 228 is picked up by the cross slot 227 of the bolt. When the bolt is rotated to its unlocked position with respect to the carrier, Fig. 6, the rear shoulders of the wing portion 228 are rotated out of registration with the grooves 232, 233 of the carrier 204 to retain the firing pin in the carrier. The bolt is provided at its forward portion with bolt stop faces 234, 235, Fig. 10, which are adapted to be engaged by a bolt stop as hereinafter described, for holding the bolt open. The front face 234 is shown in end views, Figs. 7, 13, and 14. The rear face 235 is carved into the lower left corner of the bolt directly behind the front face 234 as shown in Figs. 10 and 11.

In Figs. 27 to 37 inclusive, I have shown an alternative form of bolt mechanism which may be used for the breech closure in place of that heretofore described. In this alternate form the bolt carrier is designed to perform both the functions of a carrier and that of the cover of my first described bolt mechanism. Consequently, there are fewer parts in this second form—it will be lighter in weight and its cost of manufacture will be less than that of the first form.

The bolt 400 carries the same sort of locking lugs 140, 141 and radial arm 149 and will have the same action for opening and closing the breech as that previously described. The extractor, spring and plunger are also the same excepting that the tail of the plunger 401 has been extended and flattened to give it a limited spring action. This tail 401 projects through a bolt hole 402 in position to intercept an inward flange 403 of the carrier 404 when the carrier is in its forward position on the bolt. In this position notch 405 in the carrier flange 403 (Figs. 28 and 30) is occupied by the tail 401 of the plunger. The bolt shoulder 406, coacting with the shoulder 407 of the carrier, limits the endwise rear movement of the carrier on the bolt. The carrier partly surrounds the bolt and serves as a cover therefor. This carrier-cover member 404 carries two pairs of prongs 408, 409, 410, and 411, Figs. 30, 34, 35, and 37, which embrace the bolt and secure it to the carrier. When the bolt and attached carrier are removed from the receiver the carrier may be detached from the bolt by moving the bolt back to its limit in the carrier 25 and then rotating the bolt beyond its unlocked position, Fig. 34. The tail 401 of the plunger, acting against the side of the notch 405 of the carrier, will yieldingly resist this rotation, to prevent accidental detachment. The bolt may now be further rotated and swung downward clear of the carrier around the right hand prongs 408, 410, as a pivot, the slots 412 and 413 being formed in the surface of the bolt to provide clearances for the carrier prongs 409 and 411.

35 The firing pin 414 has an upright lug 415 whose upper end reciprocates in a slot 416 of the carrier to prevent rotation of the firing pin with respect to the carrier. The lug 415 has a helix 417. When the bolt is in its locked position, the firing pin point 418 may protrude through the bolt face 419. In that position the firing pin lug 415 with respect to the rear end 420 of the bolt is shown by Fig. 32. As the bolt is unlocked its helical cam 421, coacting with the helix 417 of the firing pin, 40 retracts the firing pin so that the lug 415 rides on the surface 422 of the bolt, Fig. 33. The firing pin has a lug 423, which lies ahead of shoulder 424 and in a recess 423' in the bolt, to retain the firing pin in the bolt. When the bolt is detached from the carrier the firing pin may be rotated to free the engagement of the firing pin lug 423 from the bolt shoulder 424 to permit the withdrawal of the firing pin.

50 The carrier 404 partakes only of sliding movement while the bolt has both a rotation in the carrier and a sliding movement relative thereto. The carrier is formed with the rib 425 on its right side near the rear end, which reciprocates in receiver groove 155a. At the left side of the carrier is the rib 426 which reciprocates in the left receiver groove 155. The receiver grooves are shown in Fig. 17. The rear end of the carrier serves to close the space between the rear end of the bolt and the end 223 of the opening of the receiver, Fig. 1.

55 The ejector 427 is mounted in a lengthwise drilled hole 436 of the bolt as shown in Fig. 28. It is assembled through the front end of the bolt, after the ejector spring 428 and the plunger 429 are inserted. In assembled position a truncated cone head 430 of the plunger 429 engages above an inclined shoulder 431 at the tail of the ejector and displaces the rear end of the ejector downward so that a hook 432 thereof will catch

against a "squared up" shoulder 433 of a radially drilled hole 434 in the bolt, Fig. 28. When the front end 435 of the ejector is forced rearwardly by a cartridge head, the rear end of the plunger 429 abuts the bottom 437 of the hole 436 and limits the inward movement of the ejector. In disassembly, a pointed tool is pressed through hole 434 against the bottom rear end of the ejector and forces the hook 432 above the "squared up" shoulder 433, whereby the ejector will drop out forwardly from the hole 436 in the bolt.

I claim:

1. The combination with the receiver of a rifle of a breech closure therefor comprising a bolt, a bolt carrier in which said bolt is rotatably mounted, a cover telescopically engaged with said bolt carrier and arranged to be in extended relation thereto when the breech is closed and in collapsed relation thereto when the breech is open, said bolt carrier being slidably engaged in a way of said receiver at one side thereof by a single lateral rib formed on said bolt carrier and said cover being slidably engaged in a way of said re-

ceiver at the other side thereof by a single lateral rib formed on said cover.

2. The combination with the receiver of a rifle of a breech closure therefor, comprising a bolt, a bolt carrier which also serves as a cover, means for mounting said bolt carrier in said receiver for reciprocable and non-rotative movement therein, means for mounting said bolt in said bolt carrier so that said bolt may have both rotatable and slidable movement therein, said bolt and bolt carrier arranged to be in extended relation to one another when the bolt is in breech closing position and in collapsed relation to one another when the bolt is in position of a full open breech, the means for mounting said bolt in said bolt carrier comprising a cylindrical portion of said bolt and embracing portions of said bolt carrier arranged to partially surround said cylindrical portion, and clearance grooves on said cylindrical portion adapted when in register with said embracing portions to permit separation of said bolt carrier and bolt.

JOHN D. PEDERSEN.
